UNITED STATES PATENT OFFICE.

GEORGE E. SHAW, OF CHICAGO, ILLINOIS.

METHOD OF PRODUCING ARTICLES FROM FIBROUS-PULP MATERIAL.

Application filed April 12, 1923. Serial No. 631,540.

My invention relates generally to methods of and means for producing articles from fibrous pulp material, but in some of its aspects it relates more particularly to the 5 production of relief work.

It has not been possible heretofore to produce relief work directly from the fibrous pulp material. When relief work of any depth is desired it has heretofore been the 10 practice to make the pulp into the form of a sheet as in the paper making process and thereafter to press or form the sheet between male and female dies. Not only is such practice slow, laborious and expensive, but it 15 is also difficult to form the relief work with sharp or well defined lines. In other words, it has been difficult to produce articles having real artistic merit. Another objection to such a method of procedure resides in the 20 fact that after the sheet material has been pressed it is in the form of a hollow or cup shaped article which it is difficult to mount or handle satisfactorily without applying a filling material. The objections to the method 25 of producing relief articles is such that they are but little used.

It is an object of my invention to provide a method of and means whereby relief articles can be formed directly from the 30 fibrous pulp materials, thus eliminating the intermediate or paper making step.

It is also an object of my invention to provide a method of and means for producing relief articles from fibrous pulp material 35 wherewith delicate, artistic lines may be accurately formed and shaped in the pulp material.

Again I aim to provide a method of and means for the manufacture of relief articles 40 directly from the fibrous pulp material, which articles shall emerge as a solid block or compress and in such shape that it can be conveniently handled, mounted or otherwise manipulated.

My invention consists generally in a method 45 of and means whereby the above named objects, together with others that will appear hereinafter are attainable, and my invention will be more readily understood by 50 reference to the accompanying drawings which illustrate the method of manufacture and mechanism suitable for practicing the same.

In said drawings:

Fig. 1 is a machine embodying my inven-

tion; the movable plunger die being shown in its outer position.

Fig. 2 is a view partly in elevation and partly in section illustrating one step in the manufacture of the article. 60

Fig. 3 is a view similar to Fig. 2 but illustrating the parts in the position which they occupy when the article has been completely formed.

Fig. 4 is a view showing the parts in the position which they occupy when the article is to be removed from the machine. 65

Fig. 5 is a face view of a perforated plate; and Fig. 6 is a face view of a wire screen, which parts are attached to the face of the 70 movable plunger die.

Fig. 7 is a perspective view of part of the machine shown in the right hand side of Fig. 4 with the die member and its containing box removed. 75

Fig. 8 is a perspective view of the die box.

Fig. 9 is a perspective view of the die box with the die positioned therein.

Fig. 10 is a face view of the embossed or relief article produced by the machine and process; and 80

Fig. 11 is a sectional view substantially along line 11—11 of Fig. 10.

My invention may be used for the manufacture of a variety of articles, of different 85 sizes, shapes and configurations, but I have chosen to illustrate the manufacture of an article in relief in the nature of a medallion. This however, should be considered as by way of illustration and not by way of limitation. 90

The machine, as here shown, comprises a cylinder 1 within which there operates a piston (not shown) and from one end of which there extends a piston plunger 2 that is attached to the piston just referred to. The parts 1 and 2 may be designated as a fluid engine designed to be operable by any liquid fluid such as steam, air, water or the like, and since it may be of usual and well-known construction, no detailed description thereof need be given. At its end the plunger 2 carries a plate 3 to which there is secured a plunger die 4. The plunger die 4 is provided with a cored opening 5, thus forming a chamber between the plate 3 and the walls of the plunger die 4. Flexible tubes 6 and 7 lead to and from the chamber 5 so that any desired heating, cooling or other medium may be conducted to and 100

105

110

from the chamber 5 for the better functioning of the die.

The remaining parts of the machine are the stationary die block 8, the pulp receiving chamber 9 and the pulp hopper 10. Mounted in the stationary die block 8 is a die and die box of novel construction. The die box in this instance, comprises an angular metal frame 11 of a size adapted snugly 10 to fit into the chamber formed in the member 9 and having a bottom wall 9a. In one wall of the member 11 there is formed a plurality of grooves or ducts 12, which serve as drainage conduits, the purpose of which will 15 be better understood shortly.

In order to produce the die, which also must be provided with ample means of drainage, I place a plurality of rods 13 through the opposite end walls of the box 20 11 (only one being shown in place and another being inserted in Fig. 8) and then force the material of which the die is formed under pressure and into the box 11. To this end the box 11 is preferably placed upon 25 some flat supporting surface with the face 14 upwardly; the material forming the body of the die placed therein substantially flush with the top face 14 and by then bringing in contact with the die material a device 30 bearing the shape or configuration which it is desired to reproduce in the medallion or other relief article being formed. Of course, in the present instance, the article would be of the shape and configuration 35 shown in the Figs. 10 and 11. The die forming device should preferably be mounted on a flat plate of a size sufficient to extend over the face 14 of the box 11 and if desired the box 11 may be provided with 40 slots or recesses in its face 14 so that the surplus material may exude therethrough. The die material 15 may be made of a number of different materials, but it must be one that will permit of the passage of water, 45 air, steam and the like, therethrough. It should also be a material which does not disintegrate when heated and which will stand a considerable working pressure. While having these characteristics, it should 50 also have the capacity of being formed into a working surface of smooth texture so that the article to be formed will present a pleasing appearance. Biscuit porcelain is one suitable material for this purpose, which it 55 will be understood is placed in the box 11 as before described with the rods 13 in place and after the die surface has been formed therein under pressure the rods 13 are removed, thus forming vertical drainage ducts 60 16 which communicate with the ducts 12 which ducts 12, in turn, communicate with the discharge openings 17 (see Figs. 2, 3 and 4). It should also be understood that after the porcelain or other die material has 65 been placed and formed in the box it is

heated or baked, thus making it hard and well adapted to withstand the necessary pressure when used for the formation of relief articles.

As another material suitable for the formation of the die, I may name a mixture comprising one part of Portland cement and two parts of crushed quartz, crushed fine but not quite so fine as the cement, say to about such a degree of fineness as will permit it to 70 pass through a ninety mesh screen. This is only intended to be a general statement of the degree of fineness, which may be varied. Instead of the crushed quartz, natural silica, sand or other suitable material may be used. 80 In making the die the cement and quartz or other material, is, of course, suitably mixed with water and placed in the die box when in plastic condition whereupon the other steps referred to when considering porcelain 85 as the die material are followed.

The pulp chamber 9 is hollow and the inner contour thereof corresponds to the outline of the article to be produced. It is adapted to be detachably secured to the stationary die block 8, to this end having formed therein openings, through which tapering pins 18 (carried by the member 9) project. The pulp chamber is provided with a receiving opening 19 which is aligned with 90 the discharge or outlet of a hopper 10, a gate or valve 21 being provided to regulate the flow of pulp. The remaining structural characteristics of the machine and the mode and operation of the method will be best 95 understood by a description of the production of an article therein.

Assuming the parts to be in the position shown in Fig. 1, at which time the plunger die will be spaced from the pulp receiving 100 chamber 9, fluid is admitted to the fluid engine, moving the plunger die to the right to a position substantially as shown in Fig. 2. At this time the fibrous pulp material 22 is admitted by means of the gate or valve 21. It should be understood that the fibrous pulp material, at this time, contains a very large percentage of water, at times as much as eighty percent. There may also be 105 trapped in the mixture, air, steam or other 110 gases. Assuming now that the fibrous pulp material is in the machine as shown in Fig. 2, power is again applied to push the plunger die 4 further to the right, thus compressing and packing the pulp material. As the pulp is compressed, it becomes more dense or solidified and offers more and more resistance to the passage of water, steam, and gases therethrough. Unless especial means 115 be provided the water, steam, air or other gases would tend to trap in the fine crevices 23 of the die, which would prevent the movement of the pulp material therewith to the result that an imperfect article 120 would result. This would be so, in matter 125

what the pressure applied might be since the water in the pulp is practically incompressible. By my novel method and by the means which I have employed, however, the pulp material while still in the relatively liquid form is permitted to flow freely into the finest crevices, the water acting as a vehicle whereupon the water passes directly through the die, which it can do because of the pervious nature thereof and into the drainage grooves or ducts 16 from which it is conducted through the ducts 12 and finally downwardly through the discharge openings 17. Thus, I am able to form directly from the pulp material articles or other work having deep relief such for example as the medallion 24, best shown in Figs. 10 and 11. While I have not described the positions shown in Figs. 3 and 4, it is thought that they are obvious. Fig. 3 merely illustrates the position of the plunger die at the limit of its right hand movement with the article completely formed therein and Fig. 4, shows the plunger die withdrawn and carrying with it the pulp chamber. The purpose of this is to permit the ready removal of the manufactured article without danger of injury thereto, but forms no part of the present invention, but on the contrary is covered by an application which I now have pending.

I have referred to the drainage through the die and I might also refer to the drainage that obtains through the perforated plate 25 and the wire screen or gauze 26 that are mounted upon the plunger die 4. I have thus provided a method and means for the production of articles in relief directly from fibrous pulp material.

From the foregoing it is evident that the die material will take up water readily by absorption and that when the semi-liquid pulp is under a pressure of about two hun-

dred pounds to the square inch, the water and air pass through the die body quickly. 45 It should also be stated that because of the extreme fineness of the pores all fine particles of solid matter are left on the face of the die and incorporated with and constitute the face of the article being formed. This 50 is one reason for the fine smooth texture of articles produced by my process. Obviously since the solid particles do not penetrate the die to any substantial extent the pores of the die remain open. 55

The many advantages thereof will be apparent to those skilled in the art to which this appertains without further comment.

I claim:

1. The method of producing a die for use 60 in the manufacture of articles from fibrous pulp material that consists in providing a box-like frame, having removable elements traversing the same, in placing a plastic cementitious material therein and forming an 65 impression surface in said material, then permitting said die to harden and thereafter removing said removable members thereby providing drainage passages in another face 70 of the die.

2. The method of producing a die for use 75 in the manufacture of articles from fibrous pulp material that consists in providing a box-like frame, having removable elements traversing the same, in placing a plaster cementitious material therein and forming an impression surface in said material, then permitting said die to harden, in then removing said removable members whereby 80 drainage passages are formed in another face of the die and in then subjecting the die to heat.

In testimony whereof, I have hereunto set my hand, this 9th day of April, 1923.

GEORGE E. SHAW.
